[21] Appl. No.: 196,516

Related U.S. Application Data

[63] Continuation-in-part of Ser. No. 125,213, March 17, 1971.

An envelope-containing multiple-page pamphlet is formed with a sheet of paper having two longitudinal parallel folds extending the length thereof, a line of adhesive adjacent one of the folds secures the sheet to the pamphlet, and the two sections adjacent the second fold are secured to each other to form the envelope, one of the sections being wider than the other and disposed between the two folds, the portion thereof adjacent the first fold being the flap of the envelope.

ENVELOPE-CONTAINING MULTIPLE PAGE PAMPHLET

This application is a continuation in part of my copending application Ser. No. 125,213, filed Mar. 17, 1971 for "Cross Folded Envelope Pamphlet," and is also copending with my application Ser. Nos. 94,052, filed Dec. 1, 1970, for "Continuous Forming of Envelopes in Pamphlets" and Ser. No. 123,543, filed Mar. 12, 1971, for "Forming Multiple Page Pamphlet" now U.S. Pat. No. 3,665,817.

This invention relates to a pamphlet having an envelope therein, and more particularly to a pamphlet containing an envelope which is formed integrally with the pamphlet and is detachably retained therein.

BACKGROUND AND OBJECTS

The prior art is replete with many forms of advertising devices containing reply postcards or envelopes. Frequently, preprinted reply postcards are formed on pages of a pamphlet, and have perforations along their edges to permit ready removal from the pamphlet. Such advertising material has become popular in recent years. However, if any questionnaire or money is to be returned, obviously a postcard is not suitable. In such cases, an envelope is required.

To overcome this difficulty, frequently envelopes have been stapled into a preformed pamphlet and are subsequently removed and mailed. This way, money or other papers may be returned in the envelope thus provided. However, the stapling of the envelope into the binding can be a time consuming and expensive process for the advertiser or publisher. A separate piece of equipment is necessary to perform the stapling operation, and this is particularly disadvantageous if the pamphlet is not ordinarily stapled, but is instead bound by gluing.

Also, many advertisers heretofore have merely inserted an envelope into a pamphlet, newspaper, or other publication loosely so that it is not bound therein. Obviously, this practice may frequently result in loss of envelopes and possible loss of sales to the advertiser.

Accordingly, it is a primary object of this invention to provide a pamphlet having an envelope formed integrally therewith.

Still another object of this invention is to provide a pamphlet having an envelope therein which may be removed therefrom.

Yet another object of this invention is to provide a pamphlet having an envelope formed therein which may be readily manufactured simultaneously with the pamphlet.

Still another object of this invention is to provide a pamphlet which may have a plurality of pages of advertising material and contain an envelope formed therein.

Yet a further object of this invention is to provide an envelope-containing pamphlet wherein the envelope may be of a variable size within certain limits.

Still a further object of this invention is to provide an envelope-containing pamphlet in which the envelope may have more than one pocket.

A still further object of this invention is to provide an envelope-containing pamphlet which may have a variety of different configurations for different purposes.

Still a further object of this invention is to provide an envelope-containing pamphlet which may be formed in a continuous operation.

DESCRIPTION OF THE DRAWINGS

These and other objects and advantages of this invention will become apparent when considered in light of the following description and claims when taken together with the drawings in which:

FIG. 1 is a perspective view of the envelope containing the pamphlet of this invention; and

FIGS. 2-9 illustrates schematically several different embodiments of this invention.

DESCRIPTION OF THE PREFERRED EMBODIMENT

With reference now to FIG. 1, the pamphlet of this invention generally designated 10, includes a first sheet of paper 12 having pages or sections 14 and 16 formed by longitudinally extending fold line 18 which extends the whole length of the pages from top to bottom. A second sheet of paper 20 is provided with parallel longitudinally extending fold lines 22 and 24 which extend the length of the sheet and are parallel and divide sheet 20 into sections 26, 28 and 30. Both sheets are fastened together by a line of adhesive disposed adjacent the first fold 24 as illustrated at 32 in FIG. 1. Pages 16 and 26 in this modification are held together by adhesive which is spaced from the fold line 18.

The envelope portion is formed from the second sheet of paper 20 by the folding of sheets 28 and 30 about the second fold line 22. Sheet 30 is less in width than sheet 28 and a flap section for the envelope adjacent fold line 24 includes an adhesive strip for the flap of the envelope and a tear-line of perforations 36. Optionally, the fold line 38 for the flap may be provided. Line 36 may also be made to coincide with fold line 24 as shown in FIG. 5. A pair of adhesive strips or lines 40 are provided between sheets 28 and 30 to hold the sheets together and form the side edges of the envelope. These strips of adhesive are slightly spaced from the second fold line 22 and extend transversely therefrom toward the flap section of the envelope. The envelope so formed will open toward the inside fold of the pamphlet. The envelope page 30 has been opened along arcuate line 42 for purposes of illustration to show the general disposition of the adhesive stripes 40 and the relationships of the various elements of the envelope.

It will be noted that the spacing between adhesive strips 40 determines the length of the envelope. If they are positioned adjacent the top and bottom edges of sheets 28 and 30, the envelope length will be the length of the pages 14 and 26. The length of pages 14, 16, and 26 is preferably the same and their top and bottom edges are in alignment, since the pamphlets are made in a continuous manner from web material and the top and bottom edges simultaneously cut as illustrated in my above-mentioned co-pending patent applications and U.S. Pat. No. 3,665,817.

If desired, a second line of perforations 44 may be provided on the outside edge of the envelope in those situations where the envelope is not to extend the full length of the adjacent sheets.

In those instances where a coin pouch or pocket is to be formed for use either with the envelope or separate therefrom, an additional adhesive strip or strips 46 are provided parallel to strips 40.

If desired, a fold line 48, similar to fold line 38 and which extends the length of page 26 adjacent the adhesive section to permit turning of the pages readily.

FIG. 4 illustrates the same pamphlet as shown in FIG. 1 in a schematic representation.

FIG. 5 illustrates a similar embodiment to that of FIGS. 1 and 4, however, in this example, section 30 is folded toward the same side of section 28 as is section 26. The result of this embodiment is that the envelope is placed so that it opens toward the center fold of the pamphlet.

In each of the preceding embodiments, it is seen that a pamphlet having six printed pages is provided.

In the embodiments of FIGS. 2 and 3, sections 14 and 16 are identical to those of FIGS. 1, 4 and 5. A second sheet 50 is provided and has folds 52 and 54 dividing sheet 50 into sections 56, 58 and 60. Adhesive stripes 62 correspond to adhesive stripes 40 of FIG. 1, and adhesive area 64 corresponds to adhesive area 34 of FIG. 1. In this embodiment, section 56 of sheet 50 is seen to be relatively narrow, and is attached over its entire area to section 16 of the first sheet. The attachment is provided preferably by adhesive, but other suitable means as previously mentioned could be utilized. In this manner, a pamphlet having four printed pages and an envelope is provided.

FIG. 3 shows a construction similar to that of FIG. 2, however, section 60' is folded toward the same side of section 58' as is section 56'. Obviously, adhesive sections 62' and 64' are on the opposite side of section 58' from that shown in FIG. 2.

Referring now to FIG. 6, a slightly different form of this invention is shown. A first sheet of paper 66 is provided as is a second sheet 68. Second sheet 68 is provided with two fold lines 70 and 72 which divide sheet 68 into sections 74, 76 and 78. Section 74 is secured to sheet 66 along a marginal edge thereof, and in this manner, a two-printed page pamphlet containing an envelope is provided. Glue areas 80 and 82 are provided as in previous examples as is a perforation line 84.

The embodiment of FIG. 7 is similar to that of FIG. 6, however, section 78' is folded toward the opposite side of section 76' than is section 74'. In this manner, the envelope opens on the outside of the pamphlet, rather than on the inside of the pamphlet as in FIG. 6.

FIGS. 8 and 9 illustrate pamphlets having four printed pages and an envelope formed therein. FIG. 8 includes a first sheet 86, and a second sheet 88. Sheet 88 has fold lines 90 and 92 which divide sheet 88 into sections 94, 96 and 98. Adhesive areas 100 and 102 are also provided on section 96 as is a fold line 104. In FIG. 8, it is seen that sections 94 and 98 are folded toward opposite sides of section 96.

In FIG. 9, the construction is essentially similar to that of FIG. 8, however, sections 94' and 98' are folded toward the same side of section 96'. Adhesive areas 100' and 102', fold line 104', and fold lines 90' and 92' are similar to the corresponding elements in FIG. 8.

Each of the foregoing embodiments of this invention may be formed in a continuous manner by the methods disclosed in my aforementioned copending applications. Additionally, any of the alternative constructions described with respect to FIG. 1 may be utilized in the embodiments of FIGS. 2 through 9 without deviating from the scope of this invention. Furthermore, addi-

tional pages may be added to the pamphlet by any suitable means, such as, for example, adhesively securing them to any of the other pages near the binding area or securing them adhesively between section 26 and sheet 12.

While this invention has been described, it will be understood that it is capable of further modification, and this application is intended to cover any variations, uses and/or adaptations of the invention following in general, the principle of the invention and including such departures from the present disclosure as come within known or customary practice in the art to which the invention pertains, and as may be applied to the essential features hereinbefore set forth, as fall within the scope of the invention or the limits of the appended claims.

What I claim is:

1. An envelope-containing multiple-page pamphlet, comprising:

- a. a first sheet of paper of a given length having a longitudinal fold line extending the entire length thereof.
- b. a second sheet of paper the same length as the first sheet,
- c. said second sheet of paper having first and second longitudinally extending parallel folds extending the length of the second sheet and dividing it respectively into first, second, and third sections,
- d. a line of adhesive between the first and second sheets for holding the sheets together with their top and bottom edges in alignment, said line of adhesive disposed adjacent said first fold line and spaced from the longitudinal fold line of the first sheet.
- e. the second section being wider than the third section of the second sheet, and these sections being folded about the second fold so as to come into direct face contact with each other to form an envelope,
- f. a pair of substantially parallel lines of adhesive spaced from the second fold line and extending between the opposed faces of the second and third sections substantially transversely away from the second fold line towards the first fold line, the lengths thereof being substantially the width of the third section so as to close the ends of the envelope,
- g. a tear line on said second section adjacent the first fold and spaced from the free edge of the third section to define an envelope flap therebetween,
- h. a line of adhesive on the flap adjacent the tear line to permit sealing of the flap.

2. An envelope-containing multiple-page pamphlet as in claim 1, and wherein:

- a. the lines of adhesive forming the envelope are disposed adjacent the top and bottom edges of the second and third sections, and
  - b. a small space between the second fold line and each of the lines of adhesive forming the envelope.
3. An envelope-containing multiple page pamphlet as in claim 1 and wherein:
    - a. said tear line includes a perforated line.
    4. An envelope-containing multiple page pamphlet as in claim 3 and including:

- a. a second fold line on said second section between said adhesive coating and said envelope along which said sealing flap may be folded for sealing said envelope.
- 5. An envelope-containing multiple page pamphlet as in claim 4 and wherein:
  - a. said perforated line is co-extensive with said first fold.
- 6. An envelope-containing multiple page pamphlet as in claim 4 and including:
  - a. a second tear line extending transversely across said second and third sections and substantially normal to said first tear line and intermediate the ends thereof for defining an envelope substantially shorter than said first fold.
- 7. An envelope-containing multiple page pamphlet as in claim 1 and wherein:
  - a. said pair of lines of adhesive are positioned adjacent the marginal edges of said second and third sections, and
  - b. at least one other adhesive stripe for dividing said envelope into two sections.
- 8. An envelope-containing multiple page pamphlet as in claim 1 and wherein:
  - a. said first section is secured over substantially its entire area to said first sheet of paper.
- 9. An envelope-containing multiple page pamphlet as in claim 1 and wherein:
  - a. said first and third sections are folded toward the same face of said second section.
- 10. An envelope-containing multiple page pamphlet as in claim 1 and wherein:
  - a. said second and third sections are each substantially wider than said first section.
- 11. An envelope-containing multiple page pamphlet

- as in claim 10 and wherein:
  - a. said first section is secured over substantially its entire area to said first sheet of paper.
- 12. An envelope-containing multiple page pamphlet as in claim 1 and wherein:
  - a. said first sheet of paper has a width substantially double that of said second section,
  - b. the fold line on said first sheet of paper dividing it into two rectangular sections of substantially equal area, and
- 13. An envelope-containing multiple page pamphlet as in claim 12 and wherein:
  - a. said first and third sections being folded toward opposite faces of said second section.
- 14. An envelope-containing multiple page pamphlet as in claim 13 and wherein:
  - a. said first and second sections are of substantially equal width.
- 15. An envelope-containing multiple page pamphlet as in claim 13 and wherein:
  - a. said second and third sections are each substantially wider than said first section.
- 16. An envelope-containing multiple page pamphlet as in claim 15 and wherein:
  - a. said first section is secured over substantially its entire area to said first sheet of paper.
- 17. An envelope-containing multiple page pamphlet as in claim 12 and wherein:
  - a. said first and third sections are folded toward the same face of said second section.
- 18. An envelope-containing multiple page pamphlet as in claim 17 and wherein:
  - a. said first and second sections are of substantially equal width.
